MAINE

TIMING DEVICE FOR LOOM STOP-MOTIONS

Application filed December 2, 1931. Serial No. 578,491.

My improved timer is devised particularly for use in any circumstance where an electrical feeler or detector is employed to detect a fault or an impending fault in the weaving of a fabric, and where it is desired to defer stopping of the loom or fabricating machine until the action of such machine has reached a certain point in its cycle or 10 operation, or has reached a certain point in one of a series of cycles.

In the accompanying drawings, the various views represent respectively:

Fig. 1, a side view elevation of so much of a loom as is necessary to show the relation of my invention thereto and its manner of action;

Fig. 2, a plan view of so much of the loom starting- and stopping-devices as is necessary to show the operation of the stop- 20 switch;

Fig. 3, a side elevation of my timer with the cover removed and looking in the direction of the arrow "a", Fig. 5, and showing the timer inactive;

Fig. 4, the same as Fig. 3 but showing the timer acting;

Fig. 5, a part sectional elevation on the line 5—5 of Fig. 4;

Fig. 6, an alternative construction of 30 the ratchet assembly;

Fig. 7, an elevation, partly sectional on the line 7—7 of Fig. 6; and

Fig. 8 is a perspective view of the spindle.

Like characters refer to like parts, 35 throughout the drawings and the specification.

Referring to Fig. 1, my timer-device 2 is shown applied to one type of loom, near 40 the foot 3 thereof. The timer 2 has a dagger 4 which extends backward toward the loom picker-stick 5 which, in turn, is mounted on the rocker 6. A bunter 7 is also mounted on the rocker 6 and is moved 45 thereby toward and from the timer 2 with movement of the rocker 6, the picker-stick 5 and the lay 8, all of which are moved together by well-known means. The relation of the timer 2 to the bunter 7 is such that 50 the timer-dagger 4 is normally held just

above the top of the bunter 7 as the latter is moved back and forth.

The timer 2 is included in, and is a part of, an electric circuit deriving its current from a source of electrical energy 9. Besides the timer 2 the circuit includes a circuit-controlling switch 10, a feeler 11, and a stop-magnet 12.

The positive side of the circuit P runs 60 from the source of energy 9 to the switch 10. From the switch 10, the positive side P of the circuit branches, one branch P' extending to and connecting with the magnet 12 and the other branch P² extending to the timer 2. The negative side of the circuit N is grounded at a convenient point 65 13 in the loom side 3. The feeler 11 is connected with the timer 2 by the positive circuit wire P³. The feeler 11 closes the circuit by connecting this positive wire P³ 70 with the loom side which is the common ground.

Referring to Figs. 3 and 4, the feeler-dagger 4 is mounted on a slide 14 in a casing 75 15. It can swing freely in a vertical plane on a pin 16. The portion 17 of the feeler-dagger which projects from the casing 15 is heavier than the portion 18 which is within the casing 15. Unrestrained, the heavier portion 17 would drop and encounter the bunter 7 as the latter moves back and forth. The feeler-dagger 4 is restrained from so dropping by the plunger 19 of a solenoid 20 mounted within the casing 15. One lead 80 21 of the solenoid winding extends to a terminal plate 22 mounted on an insulating block 23. A screw 24 extending through the back of the casing 15 serves to connect the solenoid with the branch circuit wire P⁴ 85 and through the wire P³ with the feeler 11. 90

The branch circuit wire P² from the switch 10 is similarly connected by a screw 25 with a terminal-bracket 25 to which the other lead 27 of the solenoid 20 is attached. 95 To the terminal-plate 22 is also secured a spring-metal shunt-contact or terminal 28 which extends toward the solenoid 20. The plunger 19 of the solenoid 20 carries at its bottom a plate 29 of non-magnetic metal on which is mounted a contact-pin 30. This 100

contact-pin 30 is guided by the bracket 31 and extends upwardly with its upper end near the shunt-contact 28. When the plunger 19 is raised the pin 30 encounters the shunt-contact 28 and the solenoid circuit is closed, the solenoid being maintained energized and the circuit maintained closed by the magnetic pull. When the solenoid circuit is opened, as by operation of the switch 10, the magnetic pull ceases, the plunger 19 drops and the shunt connection is broken.

When the timer-dagger 4 is released by raising of the plunger 19, its weightier end 17 falls into the path of movement of the timer-bunter 7 and is moved thereby. With the feeler-dagger 4, moves a slide 14 to which it is secured. Attached to the slide 14 is a bracket 32 having two sets of bearing-lugs 33 and 34. Between the lugs 33 is mounted a driver-pawl 35 on the pin 36. Mounted on a similar pin between the lugs 34 is an angle or bell-crank member 37. Through the vertical or pendant arm of the member 37 there is a pin 38 slidably supported thereby, the opposite end of the pin being similarly supported by the pendant arm of an angle-plate 39. The other arm of the angle plate 39 constitutes one supporting bearing for the slide 14, being secured to the casing 15 by screws 40. The opposite or dagger-supporting end of the slide 14 is supported by a plate 41 which is secured to the casing 15 by screws 42.

Surrounding the pin 38 is a spring 43 which, under compression between the angle-plate 39 and the pendant arm of the bell-crank member 37, serves to maintain the slide 14 and feeler-dagger 4 pressed toward the feeler-bunter 7 and away from the timer-ratchet wheel 44. In so doing, the horizontal arm of the bell-crank member 37 is pressed upwardly. Slidable in a hole in the slide 14 between the driver-pawl 35 and the horizontal arm of the member 37 is a pin 45 which, under the action of the spring 43 and member 37, acts to maintain the driver-pawl 35 pushed upwardly into position to properly engage the teeth of the ratchet wheel 44.

The ratchet wheel 44 is an element of what I term the "timing unit." It is mounted on a spindle 46 which consists preferably of a cylindrical body, having opposed flats 47, 47; a threaded portion 48 and a reduced end or trunnion 49, see Fig. 8. Mounted on the flattened portion 47 of the spindle 46 is the ratchet wheel 44 which is made from insulating material such as fiber. The ratchet wheel 44 has a hub 50 with a shoulder 51. Mounted on the hub 50 and lying against a shoulder 51 thereof is a contact-disk 52 having a number of peripheral lobes 61, less in number than the teeth of the ratchet wheel 44. Also mounted on the hub 65 and lying against the contact-disk 52 is a

cup-shaped distributor or contact-ring 53. The contact-disk 52 and the contact-ring 53 are secured together and to the fiber ratchet wheel 44 by rivets 54. A fiber washer 55 separates the contact-ring 53 and conjoined contact-disk 52 from the end of a boss 56 of the casing 15 in which boss, the body of the spindle 46 has a bearing. The reduced bearing portion 49 of the spindle 46 has a bearing in the plate 57 which is secured by screws 58 to the casing 15. A check-pawl 59 is also mounted on the plate 57 and is held in engagement with the fiber ratchet wheel 44 by a spring 60. The lobes 61 of the contact-disk 52, overlap certain tooth spaces of the ratchet wheel 44. When the driver-pawl 35 enters a tooth space of said ratchet wheel 44 across which tooth space one of the lobes 61 of the contact-disk extends, said driver-pawl 35, in bottoming in said tooth space, encounters the lobe 61 of the contact-disk 52. Such contact completes a continuous extent of metal, and consequently of electrical contact, from the contact-ring 53 to the loom side 3 to which the timer-case is secured and which forms the common ground for all branches of the electrical circuit. When the fiber ratchet wheel has turned one tooth, the driver-pawl 35 enters a tooth space, not overlapped by a lobe 61 of the contact-disk 52 and bottoms on the fiber, the continuity of metallic connection just described will be broken. In this instance the fiber ratchet wheel 44 has twelve teeth and the metal disk 52 is provided with four lobes 61. Consequently, metallic continuity occurs with every third impulse of the driving pawl 35.

Mounted on the insulating block 23 is a third terminal-plate 62 which, by means of a screw 63, is connected with the branch circuit P^4 which extends to the shunt-lead of the magnet 12. The magnet is of a well-known type having the same kind of shunt-device as has the solenoid 20, so that once the magnet 12 has been energized it remains energized until the circuit has been opened or broken by the switch 10. Mounted on the terminal-plate 62, just referred to, is a contact-spring or brush 64 which touches the periphery of the cup-shaped contact-ring 53.

The action of my timer may now be described. Upon near exhaustion of filling in the loom, the feeler 11 closes the feeler circuit by grounding the branch circuit P^3 in the loom-frame 3. The loom being in operation, the feeler-bunter 7 is oscillated toward and away from the timer 2. The upper extremity of said bunter 7 passes under the end of the timer-dagger 4 when the latter is in its normal or raised position. On closing of the feeler-circuit, the solenoid 20 is energized and the resultant magnetic action raises the plunger 19, releasing the dagger 4 so its heavier end 17 falls into position

to encounter the feeler-bunter 7 on its next forward swing. The plunger 19 pulled up by the solenoid 20 brings the end of the pin 30 into position to encounter the shunt-contact 28 and the magnetic pull thereupon maintains the encounter.

Impelled by the timer-bunter 7, the slide 14 which carries the timer-dagger 4 is moved. The slide 14 under the action of the timer-bunter 7 brings the driver-pawl 35 into engagement with the fiber ratchet wheel 44 moving the latter one tooth. The check-pawl 59, falling behind a corresponding tooth of the ratchet wheel 44, holds the latter to the position to which it has been advanced. Each reciprocation of the slide 14 under impulse of the timer-bunter 7 causes the fiber ratchet wheel 44 to be advanced one tooth where it is held to the advanced position by the check-pawl 59. With the relation of the components of the ratchet wheel assembly as shown in the drawings, at every third tooth space the driver-pawl 35 bottoms in and encounters one of the lobes 61 of the contact-disk 52. In this manner the magnet circuit P⁴ is grounded and closed so that the magnet 12 is energized.

The magnet 12 when energized raises the stop-dagger 66 through the connections between said stop-dagger 66 and the armature-lever 67 of said magnet 12. As the lay 8 beats back, the bunter 68 carried by the lay encounters the upheld dagger 66 and acting through the lever 69, knock-off rod 70 and dog 71, shifts or rocks the starting-handle 72 causing the loom to stop. The handle 72 in shifting moves the loom clutch-lever 73 and acting on the switch 10 opens the circuit.

40 The magnet 12 has the same shunt construction as described in connection with the solenoid 20. As this shunt-device is well known and is not claimed as such, no description is given of its details. By its action, the magnet is maintained energized until the circuit is broken between the magnet 12 and the source of energy 9.

The specific purpose of my invention is to stop the loom with the exhausted shuttle in a given box, namely, in the plain box of a 2 x 1 box-loom. The feeler is usually mounted on the breast-beam at the plain or single-box side of the loom. The feeling action takes place on the forward stroke or beat of the loom, the stopping or knock-off action usually occurring at or near the back stroke. The throw of the shuttle is initiated before the lay reaches the end of the back stroke. Consequently, should the feeler 11 effect a stopping of the loom immediately upon detection of near exhaustion of the filling on a bobbin, without intervention of the timer, the loom would be stopped with the shuttle at the side of the loom usually designated the "box-side", and not in the

plain side as is desired. By my invention, the action of the feeler 11 is to set the timer 2 into action. The timer 2 simply defers the stopping until the third pick after the feeling or detection occurs, which causes the nearly empty shuttle to be returned to the plain side of the loom when the latter stops.

70 Fig. 6 shows an alternative construction of the ratchet assembly. In this construction the fiber ratchet wheel 76 corresponds with the fiber ratchet 44 already described, certain tooth spaces 77 being cut deeper than the other tooth spaces 78. The contact-disk 79 is a flat circular plate with no lobes and of such a diameter that the periphery of the disk lies radially within the bottoms of the shallow tooth spaces 78 but overlaps the bottoms of the deeper tooth spaces 77. As the driver-pawl 35 advances the ratchet wheel 76, the shallow tooth spaces prevent it from reaching and touching the contact-disk 79. When a deep tooth space occurs during the advance of the ratchet wheel 76, the driver-pawl 35 encounters the contact-member 79, connecting it metallically and electrically with the loom side which is the common ground of all the circuits as described. In this alternative assembly the contact-ring is omitted, the brush or contact spring 64 bearing on the side of the disk-shaped contact-member 79 without intervention of a ring.

90 Without limiting myself to the precise form and arrangement of the device, I claim:

1. In a timing device for loom stop-motions, the combination with an electro-magnetic stop-device, and an electrical circuit therefor, of a timing unit in circuit with said stop device, contact means incorporated with said timing unit for closing the circuit and constituting one terminal thereof exposed at intervals by turning the timing unit, a driving member constituting the other terminal of the electric circuit to turn the timing unit and at the stated intervals encounter the exposed contact means to close the circuit, and means to impel the driving member.

100 2. In a timing device for loom stop-motions, the combination with an electro-magnetic stop-device and an electrical circuit therefor, one side of which circuit terminates in a common ground, of a rotatable terminal for said circuit, means for exposing said rotatable terminal during some intervals of rotation and for shielding it during other intervals, a driver to advance the exposing and shielding means and to make contact with the rotatable terminal when exposed, which driver is connected with the common ground and constitutes the terminal of the grounded side of the circuit, and means to actuate the driver to rotate the rotatable terminal and its exposing and shielding means, and at times to contact with the rotatable terminal to close the circuit.

3. The combination in a timing device for loom stop-motions with an electrical circuit, a driving-pawl constituting one terminal of the circuit and means to drive the pawl, 5 of a ratchet wheel not included in the circuit and driven by said pawl, and a rotating terminal for the other side of the circuit which rotating terminal is rotated by and with the ratchet wheel aforesaid when advanced by the pawl, the pawl making contact with the rotating terminal at intervals in the rotation of said ratchet wheel to close the circuit.
4. The combination in a timing device 15 for loom stop-motions with an electrical circuit, a terminal for one side of the circuit which terminal has a reciprocating movement and means to impart such reciprocating movement to said terminal, of a terminal for the other side of the circuit which terminal is normally out of contact with the reciprocating terminal, and means operated by said reciprocating terminal to periodically permit contact of said terminals to close the circuit and at intervening times prevent such contact to maintain the circuit open.
5. In a timing device for electrical stop-motions, the combination with an electrical circuit to be closed, a rotating timing unit 20 and reciprocating means to rotate said unit to close and to open said circuit, of a continuously moving bunter, a dagger carried adjacent the path of movement of the bunter by said reciprocating means, means to restrain said dagger from engaging the bunter, a solenoid to release said restraining means and permit the dagger to fall into engagement with the bunter so the latter actuates the reciprocating means, an auxiliary circuit to energize the solenoid, and means to close said auxiliary circuit.
6. In a timing control for the timing device of a loom stop-motion, the combination with a stop-motion circuit, of a rotatable 25 terminal for one side of said circuit, a reciprocating terminal for the other side of the circuit, a member that carries the rotatable terminal which member is engaged by and advanced rotatively by said reciprocating terminal and at intervals in such rotative advance presents the surface of the rotatable terminal to the reciprocating terminal, and means to operatively move the reciprocating terminal to turn the rotatable 30 terminal and at intervals make contact therewith to close the stop-motion circuit.
7. In a timing device for electrical stop-motions, the combination with the stop-motion magnet and circuit therefor, of a rotatable timing unit to intermittently close said circuit, reciprocable means to rotate said timing unit, a bunter reciprocating adjacent said reciprocable means, a dagger engageable with said bunter to communicate reciprocation of the bunter to the reciprocable means, but normally restrained from such engagement, electro-magnetic control to restrain and to release said dagger, an auxiliary circuit for the electro-magnetic control, and means to close said auxiliary 70 circuit to energize said electro-magnetic control.
8. In a timing device for electrical stop-motions, the combination with the stop-motion magnet and circuit therefor, of a rotatable timing unit to intermittently close said circuit, a pawl movable to advance said unit rotatively, a slide to carry and reciprocate the pawl, a dagger carried by the slide and free to drop when unrestrained, an electro-magnetic control for the dagger, an auxiliary circuit for the control, means to close said auxiliary circuit to release the dagger and permit it to drop, a reciprocating bunter to encounter the dropped dagger and through it communicate the reciprocating movement of the bunter to the slide, and means to reciprocate said bunter.
9. In a timing device for loom stop-motions, the combination with an electro-magnetic stop-device and an electric circuit therefor, of a timing unit in circuit with said stop-device, contact means incorporated with said timing unit for closing said stop-motion circuit, another electro-magnetic device to cause the timing unit to act, and means intermediate said device and said unit to secure such action.
10. In an electrical stop system for looms, the combination with the stopping apparatus of a loom, of an electro-magnetic device for actuating the stopping apparatus of the loom, means to operatively connect said apparatus and device, a feeler for initiating the action of said electro-magnetic stopping-device, electric circuits for said device and feeler, a common source of electric current to serve said circuits, a timing unit operative from the loom action to close the electro-magnetic stopping circuit at lapse of 100 a definite interval after the feeler action, a second electro-magnetic device in the feeler circuit to control the timer unit from the feeler, and means controlled by the second electro-magnetic device for transmitting the 105 loom action to the timer unit.
- In testimony whereof I hereunto affix my signature.
- EDWIN C. SMITH.
